(57) **CLAIM**

The ornamental design for a compressor for home appliance, vehicle and aircraft, as shown and described.

DESCRIPTION

FIG. 1 is a front elevation view of a compressor for home appliance, vehicle and aircraft showing the first embodiment of our design;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a perspective view thereof;

FIG. 8 is a front elevation view of a compressor for home appliance, vehicle and aircraft showing the second embodiment of our design;

FIG. 9 is a rear elevation view thereof;

FIG. 10 is a left elevation view thereof;

FIG. 11 is a right elevation view thereof;

FIG. 12 is a top plan view thereof; and,

FIG. 13 is a bottom plan view thereof.

The broken lines in the figures, consisting of evenly sized dashes, depict portions of the compressor for home appliance, vehicle and aircraft that form no part of the claimed design; the broken lines, consisting of unevenly sized dashes, define the boundary of the claimed design, which extends to the boundary but does not include the boundary.
